COSMETIC CONTAINER

Robert B. Hopgood, Cheshire, Conn., assignor to The Eyelet Specialty Company, Waterbury, Conn., a corporation of Connecticut

Application June 30, 1955, Serial No. 519,103

13 Claims. (Cl. 206—56)

My invention relates to a cosmetic-container construction and is particularly concerned with such constructions in which the closure cap is frictionally retained when placed over the container body.

It is an object of the invention to provide an improved construction of the character indicated.

It is another object to provide an improved cosmetic-container construction, characterized by relatively easy action in the placement and removal of a closure cap.

It is a further object to meet the above objects with a construction featuring reduced axial play and improved smoothness of action in the propulsion of a cosmetic.

It is still another object to meet the above objects with a construction in which the placement of the closure cap inherently tends to more tightly frictionally engage relatively rotatable parts, whereby inadvertent propulsion of the lipstick is avoided while the closure cap is in place.

It is another object to meet the above objects with improved means for frictionally engaging a closure cap to a container.

Other objects and various further features of novelty and invention will become apparent or will occur to those skilled in the art from a reading of the following specification in conjunction with the accompanying drawings. In said drawings, which show, for illustrative purposes only, preferred forms of the invention:

Fig. 1 is a vertical sectional view of a cosmetic container incorporating features of my invention, but shown with the closure cap removed and with the friction member therefor in its unstressed position, in readiness to develop gentle frictional engagement with a closure cap;

Fig. 2 is a fragmentary view similar to Fig. 1 to illustrate the relation of parts when the closure cap is in place;

Figs. 3 and 4 are enlarged vertical sectional views of the friction member of Figs. 1 and 2, and shown for the unstressed and stressed conditions thereof, respectively;

Figs. 5 and 6 are perspective views of a modified friction member, shown respectively in the unstressed and stressed conditions thereof;

Fig. 7 is a view similar to Fig. 3, but illustrating a further modification;

Fig. 8 is a fragmentary vertical sectional view similar to Fig. 1 to illustrate a modification; and

Figs. 9 and 10 are similar vertical sectional views to illustrate still further modifications.

Briefly stated, my invention in a preferred form contemplates improved means for frictionally retaining a closure cap when placed over the body of a cosmetic container. My friction member is characterized particularly by a generally conically developed outwardly flaring skirt, retained by the container body and flaring freely outwardly, to an extent permitting resilient interception of the bore of the closure cap as the latter is placed over the container. The small end of the skirt is retained on the container body, as against a circumferential bead, or by forming said small end with a radially inwardly extending portion located in a groove or be-

2

tween shoulders on the body. Preferably, this radially inwardly extending portion is so formed as to serve certain further functions, particularly useful in swivel-type or self-propelling lipsticks involving inner and outer relatively rotatable tubular body elements. The nature of this inwardly extending portion is such as lightly axially to load the relatively rotatable parts and thus eliminate rattle or axial play therebetween. The nature of my construction is further such that, upon placement of the closure cap, the skirt is inwardly deflected and the radial flange is axially deflected, thus increasing the axial load on the relatively rotatable parts and providing increased friction, for resistance of inadvertent rotation of the parts when the container is closed.

Referring to Figs. 1 and 2 of the drawings, my invention is shown in application to a swivel-type or self-propelling rotary lipstick container, comprising inner and outer sleeve members 10—11 having cam slots 12—13 formed therein for engagement with the follower 14 of a carrier cup 15, for a lipstick or the like 16. In the form shown, a circumferential bead 17 constitutes a radially outward flange or limiting means for axially locating one end of the outer tubular member 11, and a radial flange or shoulder 18 limits or axially locates the other end of the outer tubular member 11. The inner tubular member is completed by a cylindrical land 19 connecting the shoulder 18 to an enlarged base or actuating-knob portion 20, constituting the closed end of the inner tubular member 10. For appearance sake, I have provided a casing 21 to retain the outer tubular member or sleeve 11, and I show a snap lug 22 formed out of the casing 21 and projecting inwardly to engage a corresponding hole 23 in the sleeve 11, for holding the parts together.

In accordance with the invention, I provide a resilient skirt or circumferentially extending member 24 carried by the container body in such manner as to position a free outwardly extending lip 25 thereof in intercepting relation with the bore of the closure cap 26 to be placed over the open end 27 of the container. The maximum unstressed outer diameter of the skirt portion 25 preferably exceeds the bore diameter of the closure cap 26, so that placement of the closure cap will be accompanied by radially inward deformation of the skirt 25, with resultant light, easy-acting frictional engagement of the parts and retention of the closure cap. The parts are shown in Fig. 2 in their relationship when the closure cap 26 has been placed into fully assembled relation with the base 20 and in abutment with the shoulder 18 thereof.

The resilient member 24 may be of gently yieldable material, such as polyethylene or an equivalent plastic, and preferably includes, in addition to the skirt 25, means formed integrally with the small end thereof and extending generally radially inwardly, for axial location by the retention means formed on the body of the container. In the form shown, the radially inwardly extending part is a radial flange 29, so formed as to seat on the shoulder 18 and to substantially close off the axial clearance between shoulder 18 and the sleeve and casing 11—21. The radially extending flange 29 is preferably somewhat frusto-conically formed, even in the unstressed condition shown in Fig. 3, and may be viewed as a dished resilient washer, lightly loading the parts 11—21 to eliminate axial play. Fig. 4 shows that when stressed by placement of the closure cap 26 in the position of Fig. 2, the skirt 25 is radially inwardly deformed, while the radial flange 29 is axially distended. The axial distention of flange 29 will be understood to add to the normal resilient axial loading imparted by flange 29 to the relatively rotatable tubular members 10—11, particularly when the container is closed and capped. The added friction thus developed adds to the ability of the mechanism to resist relative rotation, so that the likeli-

hood of cosmetic damage due to inadvertent propulsion against the inside of the closure cap is rendered remote.

The modification shown in Figs. 5 and 6 differs from the described form of Figs. 3 and 4 only in that the radial-flange portion 29' is, in effect, a peripheral succession of similar radially inwardly directed lugs 30-31, defined by radial serrations or slits 32. It will be appreciated that provision of slits 32 may, for certain materials and material thicknesses, promote greater axial distention of the radial flange 29' and, therefore, added frictional loading of the relatively rotatable parts, when the skirt 25 is radially compressed by a closure cap, as shown in Fig. 6.

In Fig. 7, I illustrate a circumferentially extending member 24' which may, in all respects, resemble the member 24 of Figs. 3 and 4, except that I provide a reinforcement or stiffening member 33 carried by or molded within the body of the member 24'. Stiffening member 33 may be one of an angularly spaced plurality, but I have shown only one such member. Member 33 extends for substantially the full axial length of the skirt 25 and for substantially the full radially inward extent of the flange 29. It will be appreciated that, upon placement of the closure cap over the skirt 25, with accompanying radially inward deformation of skirt 25, the reinforcement member 33 will serve as a bellcrank, undergoing partial clockwise rotation in the sense of Fig. 7, and more positively driving a local portion of the radial flange 29 into frictional engagement with the adjacent axial end of the sleeve or casing 11-21.

For situations in which the peripheral friction-engagement function is not important, the member 24' may be viewed merely as a means for flexibly supporting the bellcrank 33. The axially extending arm of bellcrank 33 projects outwardly for interception by the closure cap, and the radially extending arm thereof is driven axially into frictional engagement with parts 11-21 when the closure cap is placed over the container.

In Fig. 8, I show application of my invention to another construction in which peripherally continuous friction engagement may not be an important requirement, but in which light frictional engagement of the closure cap to the base is significant. The container may be generally as described in Fig. 1 and therefore, where applicable, the same reference numerals are employed. However, the resilient member 35 is formed with a skirt more or less tightly fitting and adhering to the land 19, except for one or more bulbous friction lobes 36, for light contact with the bore of the closure cap. As will be seen from the left lobe 36 of Fig. 8, I prefer that the lobe 36 shall be hollow for easy resilient inward deformation, and that the radial flange 29 shall be conically dished, and therefore lightly axially loaded against parts 11-21, as explained above in connection with other figures.

In the container of Fig. 9, the lipstick or the like is held in a carrier 40 having a finger-actuating piece 41, accessible externally through a guide slot 42 in the single tubular body member 43. For assembly purposes, the upper end 44 of the slot 42 is open; the lower end of the body 43 is preferably closed by an enlarged base 45. My resilient skirt 46 is shown to be formed integrally with a radially inwardly extending portion 47 for axial location between the walls or flanges 48-49, defining a recess or groove in the body 43. The skirt 46 flares outwardly over a land 50 to an extent such that, upon placement of the closure cap 51, gentle frictional engagement is promoted.

In the arrangement of Fig. 10, a circumferential flange or bead 55 serves as the primary retaining means for the resilient member 56. Other parts resemble those of Fig. 9 and are therefore given the same reference numbers, but with primed notation. The unstressed minimum radial dimension of member 56 is preferably slightly less than the outer diameter of the land 50',

so that even though axially retained by bead 55, member 56 will tend to resiliently hug the land 50'. Frictional engagement with and retention of the closure cap 51 are otherwise as described for Fig. 9.

It will be seen that I have described a relatively simple container construction having features of smooth frictional engagement of the closure cap, without development of undue stickiness in the placement or removal of the closure cap. My mechanism is such that axial play may be avoided between the relatively rotatable parts, and yet rotation is easy and smooth when dispensing or retracting the lipstick. Nevertheless, upon placement of the closure cap, not only is the aforementioned friction engagement developed, but the parts are inherently frictionally loaded or lightly jammed against inadvertent relative-rotation displacement, so that contact of the lipstick with the inside of the closure cap may be avoided.

While I have described the invention in detail for the preferred forms shown, it will be understood that modifications may be made within the scope of the invention as defined in the claims which follow.

I claim:

1. In a cosmetic container of the character indicated, a tubular body, means for supporting a lipstick or the like within said body and for dispensing the same out one end of said body, a base including a generally cylindrical land and radial shoulder joining the same to said body, a circumferentially resilient member having a radially inwardly extending portion seated on said shoulder and an axially extending circumferentially continuous skirt flaring outward in the direction away from said inwardly extending portion, and a closure cap fitting over said one end and of inner diameter intermediate the maximum and minimum outer diameters of said skirt, whereby upon placement of said closure cap over said skirt, said cap and base will be frictionally retained in assembled relation.

2. In a cosmetic container of the character indicated, an elongated tubular body, means for supporting a lipstick or the like within said body and for dispensing the same out one end of said body, said body having a pair of axially spaced radial shoulders, a circumferentially extending resilient member having a radially inwardly extending portion retained between said shoulders and an axially extending skirt circumferentially continuously flaring outwardly in the direction away from said inwardly extending portion, and a closure cap fitting over said one end and of an inner diameter to deflect said skirt for resilient engagement with said skirt.

3. A container according to claim 2, in which said body is essentially a single continuous tubular piece with a circumferential groove formed therein between said shoulders.

4. A container according to claim 2, in which said body comprises inner and outer relatively rotatable elements, one of said shoulders being formed at said other end of said inner tubular element and extending radially outwardly, the other of said shoulders being defined by the adjacent axial end of said outer tubular element, whereby on relative rotation of said elements, said resilient member serves the added function of providing a bearing surface for sustaining smooth relative rotation of said members.

5. In a cosmetic container of the character indicated, inner and outer relatively rotatable tubular body members, axially spaced circumferentially and radially outwardly extending locating means on one of said members and serving axially to locate the other of said members, means for supporting a lipstick or the like within said body and including means cooperating with said relatively rotatable members to propel the same toward one end of said container upon relative rotation, a circumferentially extending resilient element circumferentially continuously riding one of said locating means and the adjacent axial end of the other of said tubular members, said resilient element including as an integral part thereof

a circumferentially continuous plastic skirt flaring outwardly in the direction away from said one end, and a closure cap fitting over said one end of said container and frictionally engaged with said skirt.

6. In a container of the character indicated, means for supporting a lipstick or the like, inner and outer tubular members embracing said means and having cam elements cooperating with said means to propel the same upon relative rotation of said tubular members, the inner of said tubular members having at one axial end a radially outwardly extending shoulder of an outer diameter at least overlapping said outer tubular member, a circumferentially extending resilient member including a radially inwardly extending flange axially retained between said shoulder and the adjacent end of said outer tubular member, said resilient member having an outwardly flaring circumferentially continuous resilient skirt of maximum outwardly flared unstressed diameter exceeding the maximum diameter of said outer tubular member, and a closure cap fitting over said members and having an inner diameter less than the maximum unstressed diameter of said skirt and in frictional engagement with said skirt.

7. In a cosmetic container of the character indicated, inner and outer relatively rotatable tubular body members, axially spaced circumferentially and radially outwardly extending locating means on one of said members and serving axially to locate the other of said members, means for supporting a lipstick or the like within said body and including means cooperating with said relatively rotatable members to propel the same toward one end of said container upon relative rotation, a closure cap for covering one end of said container and fitting over both said locating means, and a circumferentially extending flared resilient skirt circumferentially continuously riding one of said locating means at the smaller end of said skirt, the flare of said skirt being outward in the direction away from said one end and to an extent exceeding the bore of said cap, the axial end of the other tubular member adjacent said skirt being of a sufficient maximum diameter to ride the adjacent axial end of said skirt.

8. In a cosmetic container of the character indicated, inner and outer relatively rotatable tubular body members, said inner member having an open end and an enlarged base closing the other end, carrier means within said inner member and including means engageable with said body members to advance and retract the same on relative rotation of said members, first axial locating

means on said members for retaining said outer member against displacement in the direction of said open end, a circumferentially continuous element at the enlargement of said base and the adjacent axial end of said outer member, said circumferentially continuous element including a generally radially inwardly extending member and a circumferentially continuous resilient skirt, said skirt flaring normally outwardly in the direction away from said open end, and a closure cap fitting over the open end of said container and having a bore frictionally engaging said skirt; whereby, on engagement of said skirt by said closure cap, said generally radially inwardly extending member will be axially deflected in the direction of applying increasing axial loading between said inner and outer members with increasing inward deflection of said generally axially extending member.

9. A container according to claim 8, in which said generally radially extending member is a generally radial flange on said circumferentially continuous element.

10. A container according to claim 9, in which the inner limit of said flange is continuous.

11. A container according to claim 9, in which the inner limit of said flange is serrated, thereby dividing said flange into an angularly spaced plurality of radially inwardly extending lugs.

12. A container according to claim 8, in which said generally radially extending member and said skirt are integrally formed of a single piece of plastic material.

13. In a cosmetic container of the character indicated, an elongated tubular body, means for supporting a lipstick or the like within said body and for dispensing the same out one end of said body, said body having a pair of axially spaced radial shoulders, a circumferentially continuous yieldable plastic skirt member including at its upper end a radially inwardly flange axially retained between said shoulders, said skirt member being flared outwardly in the direction away from the dispensing end of said body, and a closure cap fitting over said open end and of an inner diameter to engage the flare of said skirt for resilient frictional engagement therewith.
